ENGINE STARTER CONTROL

Malcolm P. Ferguson, Elmira, N. Y., assignor to
 Eclipse Machine Company, Elmira, N. Y., a corporation of New York

Application December 23, 1931, Serial No. 582,861

3 Claims. (Cl. 123—179)

This invention relates to an engine starter control and more particularly to a device for engaging and operating a starting mechanism by a manual control member for the engine such as the accelerator pedal.

Starter gearing of the manual shift type is usually controlled by a separate pedal the depression of which first causes a starting pinion to be moved into engagement with a member of the engine to be started such as a flywheel gear, and thereafter causes the starting switch to be closed. According to the present invention, this special pedal is dispensed with and the function thereof is performed by one of the manual control members for the engine such as the accelerator pedal, under the control of an automatic disconnecting means responsive to self-operation of the engine.

It is an object of the present invention to provide a novel device for operating a starter of the manual shift type from an engine control member.

Another object of the invention is to provide such a device which is arranged to automatically disconnect the control member from the starting mechanism when the engine is running.

A further object is to provide such a device which embodies provisions for preventing such disconnection during the cranking operation.

Further objects and advantages will be apparent to those skilled in this art from the following description taken in connection with the accompanying drawing in which:—

Fig. 1 is a somewhat diagrammatic showing of one preferred embodiment of the invention, the parts being shown in elevation and partly in section; and

Fig. 2 is a similar view showing the parts in cranking position.

Referring to Fig. 1, engine starter mechanism of the manual shift type is illustrated comprising a motor 1 with a starting switch 2 mounted thereon and with an extended armature shaft 3 on which is mounted a starting pinion 4 in position to be slid into and out of engagement with a member such as flywheel gear 5 of an engine to be started. Pinion 4 is driven from the armature shaft 3 through an overrunning clutch 6 which engages a splined portion 7, (Fig. 2) of the armature shaft. Means are provided for shifting the pinion 4 into and out of mesh with the flywheel gear 5 in the form of a shifting fork lever 8 pivoted at 9 in a housing 11, and having a link 12 pivoted to the free end thereof.

A manual control member for the engine such

as an accelerator pedal is illustrated at 13 and is provided with link 14 connected to a lever 15 having a fixed pivot 16 at one end and provided at its free end with a link 17 arranged to operate a controlling device for the engine fuel such as a carburetor throttle, not illustrated. A return spring 18 is preferably provided for normally retaining the accelerator pedal 13 in the position shown in Fig. 1. According to the present invention, connecting means are provided for shifting the pinion 4 into engagement with the flywheel gear 5 and for closing the starting switch 2 upon depression of the accelerator pedal 13. As here shown, this connection is in the form of a sleeve member 19 rigidly fixed to the free end 15 of the link 12 as indicated at 21, and a push link 22 pivoted at 23 to the lever 15 and having its free end slidably received within the sleeve member 19. The push link 22 is normally connected to the sleeve 19 by means of a sliding latch 20 member 24 formed as a piston loosely mounted in a cylinder 25 extending at right angles from the sleeve member 19 and normally arranged with its lower end in the path of a shoulder 26 formed on the push link 22.

Means are provided for disabling the connecting means by withdrawing the latch 24 from the path of the shoulder 26 in response to self-operation of the engine, such means as here illustrated comprising a device for causing a pressure differential to act on the latch 24 to move it into inoperative position when the engine starts. As illustrated in Fig. 1, this means comprises an engine driven air pump A connected by means of flexible conduits 27 and 28 to the cylinder 25. In the arrangement shown, connection is made to the inlet of the air pump whereby the vacuum produced by said pump raises the latch 24. As illustrated in Fig. 2, the source of vacuum may be the intake system of the engine, a portion of which such as the intake manifold is illustrated at 29. Obviously, the connection may be made to the pressure side of the air pump if so desired by merely forming the latch 24 to be pressed away from the pump instead of toward the pump to disconnect it from the link 22.

Means are provided for preventing the withdrawal of the latch 24 during the cranking operation, such means being here illustrated as a valve 31 pivotally mounted at 32 and arranged to connect the flexible conduits 27 and 28. Valve 31 is provided with a slidably cut-off plunger 33 which is pivoted at 34 to the cylinder 25 whereby longitudinal motion of the sleeve 19 causes the plunger 33 to seat in and close the valve 31.

A yielding connection indicated generally at 35 is preferably provided for the plunger 33 in order to allow continued motion of the sleeve member 19 after the closure of valve 31.

5 In the operation of the device, starting with the parts illustrated in Fig. 1, depression of the accelerator pedal 13 causes the push link 22 to engage the latch 24 and move sleeve member 19 whereby the shifting fork 8 is swung in a direction 10 to shift the starting pinion 4 into engagement with the flywheel gear 5. After such engagement of the gearing has been effected, further motion of the shifting lever 8 causes closure of the starting switch 2 whereupon the starting motor 1 is energized and cranking takes place. The 15 initial movement of the sleeve member 19 causes the plunger 33 to move to closed position as illustrated in Fig. 2 whereby any vacuum created by the vacuum pump or in the intake manifold 29 20 as the case may be, is prevented from acting on the latch member 24.

When the engine starts, release of the accelerator pedal 13 by the operator allows the parts of the starting mechanism to return to normal position, but consequent opening of the valve 31 25 allows the vacuum caused by the self-operation of the engine to withdraw the latch 24 and hold the same out of the path of shoulder 26 on the push link 22 so long as the engine is in operation. The accelerator pedal 13 is thus free to control the 30 admission of fuel to the engine in the usual manner without operating the starting mechanism since the push link 22 is then freely slidable within the sleeve member 19.

35 Should the engine stall for any reason, the dissipation of the vacuum caused by the operation of the engine causes the latch 24 to fall into the path of the shoulder 26 whereupon depression of the accelerator pedal will cause the reengagement of the starter gearing and energization of 40 the starting motor as above described.

45 Although but one form of the invention has been shown and described in detail, it will be understood that other forms are possible and various changes may be made in the proportions and arrangements of the parts without departing from the spirit of the invention as defined in the claims appended hereto.

What is claimed is:

1. In combination with an internal combustion engine, an electrical starting system therefor including a starting motor, a starting switch and disconnectible gearing for driving the engine 5 from the starting motor, a manual member for controlling the fuel supply of the engine, connecting means including a movable latch whereby operation of the manual member moves the gear into engagement and closes the starting 10 switch, means responsive to rotation of the engine for creating a fluid pressure differential, means responsive to said pressure differential for moving said latch to inoperative position and means for preventing the action of said pressure on said 15 latch during the starting operation.

2. In combination with an internal combustion engine, an electrical starting system therefor including a starting motor, a starting switch and disconnectible gearing for driving the engine 20 from the starting motor, a manual member for controlling the fuel supply of the engine, connecting means including a movable latch whereby 25 operation of the manual member moves the gear into engagement and closes the starting switch, means responsive to rotation of the engine for creating a fluid pressure differential, means responsive to said pressure differential for moving said latch to inoperative position, a valve for preventing the action of said pressure on said 30 latch, and means for actuating said valve incidental to the actuation of the starting system.

3. In combination with an internal combustion engine, starter gearing therefor including a motor driven pinion, means for mounting said pinion so as to be manually shiftable into and out of engagement with a member of the engine to be started, a manual control member for said engine, connecting means normally operative for shifting said pinion by said manual member, means responsive to self-operation of the engine for disabling said connecting means and means responsive to actuation of the connecting means for preventing the operation of said disabling 45 means when the pinion is in engagement with the engine member.

MALCOLM P. FERGUSON.
